(57) **CLAIM**

The ornamental design for a hairdryer, as shown and
described.

DESCRIPTION

FIG. 1 is a front perspective view of a hairdryer, showing our
new design;

FIG. 2 is a rear perspective view thereof;

FIG. 3 is an exploded perspective view of the hairdryer;

FIG. 4 is a front view of the hairdryer;

FIG. 5 is a rear view thereof;

FIG. 6 is a left side view thereof;

FIG. 7 is a right side view thereof;

FIG. 8 is a top view thereof;

FIG. 9 is a bottom view thereof; and,

FIG. 10 is an enlarged detail view of a portion of the
hairdryer shown in area 10 in FIG. 2.

The broken lines in the drawings illustrate the portions of the
hairdryer that form no part of the claimed design.

The dash-dot-dash broken lines encircling the enlarged
views are for annotative purposes only and form no part of
the claim thereof.

1 Claim, 10 Drawing Sheets
